UNITED STATES PATENT OFFICE.

MYRON E. MOORE, OF DEERING CENTRE, ASSIGNOR OF ONE-HALF TO
ELIJAH G. GOULD, OF WOODFORD'S, MAINE.

VENTILATING-SHUTTER.

SPECIFICATION forming part of Letters Patent No. 424,015, dated March 25, 1890.

Application filed August 31, 1889. Serial No. 322,586. (No model.)

To all whom it may concern:

Be it known that I, MYRON E. MOORE, a citizen of the United States, residing at Deering Centre, in the county of Cumberland and State 5 of Maine, have invented a new and useful Operating Device for Ventilating-Shutters, of which the following is a specification.

This invention has relation to operating devices for opening and closing ventilating- 10 shutters for cars and coaches; and among the objects in view are to provide for a simultaneous opening or closing of the entire series of shutters, and that by a cheap and economical construction.

15 The invention consists in certain features of construction, hereinafter specified, and particularly pointed out in the claim.

Referring to the drawings, Figure 1 is a perspective of the interior of the sides of the car 20 provided with ventilating-shutters and operating devices therefor constructed in accordance with my invention. Fig. 2 is a transverse section with dotted lines showing the shutter closed. Fig. 3 is a detail in perspective of a section of the rock-shaft and rock-arm.

Like numerals of reference indicate like parts in all the figures.

1 represents the side of the car or coach, 30 and 2 a series of openings for the purpose of ventilation, and in the same are mounted pivotally the shutters 3, the lower edges of which abut against beads 4, located upon the sills of the openings, whereby the bottom rail of the 35 shutter is prevented from inward swing beyond the bead.

5 represents brackets secured along the side of the upright intermediate of each of the shutters, said brackets terminating at their upper 40 ends in bearing-eyes 6, the entire series being in line with each other. In the bearing-eyes 6 is loosely journaled a rock-shaft 7, the ends of which outside of the bearings are dropped to form handles 8 for operating the shaft.

45 Mounted upon the shaft and at such points thereof as occur opposite the center of each shutter are rock-arms 9, in this instance formed of light sheet metal, the inner ends of which are bent to form an eye for receiving 50 the rod, as at 10, and are bolted by bolts 11

rigidly upon the rod, so as to move therewith. The outer ends of the rock-arms are bent to form eyes 11*, and form one member of a hinge joint, the opposite member of the joint being formed by the inner ends of links 55 12, which are bent to form eyes 13, aligning with the eyes 11*, and through the same is passed a pintle 14.

15 represents a hinge-leaf with which each of the shutters are provided below their pivots, said leaf having a pair of eyes 15*, which align with an eye 16*, formed on the outer end of each of the links, and through the same are passed pintles 16. Screws 17 connect the hinge-leaves to the shutters, and it 65 will be apparent that by raising the drop-handles of the rock-shaft and by reason of the hinged connections described the shutters will be swung to an open position, as shown in Fig. 2, the rock-arms and their respective links being brought into line with each other and forming a rigid brace for supporting the shutters. By lowering the drop-handles the rock-shaft will be partially rotated in an opposite direction, and the rock- 70 arms and their links folded, as shown by dotted lines in Fig. 2. It is also apparent that by operating the handles described all of the shutters will be simultaneously operated. If desired, however, I may use a series of rock- 75 shafts each terminating in handles and each governing and operating a certain number of shutters, thereby opening and closing a section, say, of three or four shutters at one time, and thus cooling or warming the atmosphere in accordance with the desires of passengers located in the vicinity of the respective sections.

Having thus described my invention, what I claim, and desire to secure by Letters Patent, 80 90 is—

The combination, with the side of a car having a series of ventilating-openings and pivoted shutters mounted in the openings, of a series of brackets secured to the car and 95 terminating at their opposite ends in bearings, a rock-shaft mounted in the bearings and terminating in handles, and a series of rock-arms, the lower ends of which are bent to embrace and bolted to the rock-shaft oppo- 100

site each of the shutters, and having their outer ends bent to form one member of a hinge-joint, links for each of the rock-arms having their inner ends bent to form the opposite member of the joint, and pintles for connecting said members, and hinge-leaves secured to each of the shutters near their lower end and terminating in eyes forming one member of the hinge-joint and aligning 10 with an eye upon the outer ends of the links

and pintles for insertion through the same, substantially as specified.

In testimony that I claim the foregoing as my own I have hereto affixed my signature in presence of two witnesses.

MYRON E. MOORE.
